UNITED STATES PATENT OFFICE.

EMILE HARLET, OF FIVES-LILLE, FRANCE.

LOCOMOTIVE BLAST-PIPE.

1,344,887.

Specification of Letters Patent. Patented June 29, 1920.

Application filed April 10, 1919. Serial No. 289,086.

To all whom it may concern:

Be it known that I, EMILE HARLET, citizen of the Republic of France, and resident of Fives-Lille, (post-office address 19 Rue Berlioz, Nord,) have invented certain new and useful Improvements in Locomotive Blast-Pipes, which improvements are fully set forth in the following specification.

The present invention has for its object 10 to provide a blast pipe which cannot be put out of order and which is of constant height for locomotives, locomobiles and other apparatus which use exhaust steam, such blast pipe being of variable annular and central 15 sections and which has its movement balanced.

This blast pipe, by the very form of the annular jet, insures a natural expansion of the steam, augmenting the surface of contact with the gases, and it permits, on the other hand, a direct evacuation of the steam without loss of velocity, by offering it a greater section of evacuation than with the already known devices. These advantages 25 are indicated by a diminution of the back pressure on the pistons and an economy in fuel.

The locomotive blast pipe which forms the subject matter of the present invention 30 is represented, by way of example, in the accompanying drawings.

Figures 1 and 2 show, respectively, a view in vertical section and a view in plan of a blast pipe according to the invention, supposed to be in the open position.

Figs. 3 and 4 are similar views to the preceding ones, relating to the closed position.

Figs. 5 and 6 show, in front elevation and plan, one of the two valves constituting the 40 device.

Fig. 7 is a detail diagram relating to a modification of the device which operates the valves.

Figs. 8 and 9 are views in vertical section 45 and plan of another constructional form of the blast pipe, supposed to be in the closed position.

Figs. 10 and 11 show the blast pipe in the open position.

Figs. 12 and 13 show a view in vertical 50 section and a view in plan of another blast pipe according to the present invention, supposed to be in the open position.

Fig. 14 is a view in plan of this blast pipe 55 in the closed position.

Reference will first be made to Figs. 1 to 6. It will be seen that the invention may be constituted by two valves *b* placed in the blast pipe *a* and pivoted at their central part, on studs *c* fixed to the pipe and adapted to be operated by a lever *d* provided with slots of suitable form, in which engage the cross-rods *e* fixed to the valves *b*.

In the position in which the blast pipe is completely open (see Figs. 1 and 2), the valves *b* are open at the bottom, leaving a central passage *f* for the steam the evacuation of which is thus effected in a direct manner and without loss of velocity. These valves, the use of which is double, leave also 70 around them an annular passage *g* which is slightly larger at its lower part, through which the steam escapes rapidly. By providing the blast pipe *a* with corrugations *h*, an expansion or mixing of the jet can be 75 obtained which, by reason of its unequal thickness, insures a dilation of the steam at the outlet. It follows that the jet continues to expand, thus augmenting the surface of contact with the gases. 80

In the position in which the blast pipe is closed at the bottom (see Figs. 3 and 4), the valves *b* are applied one against the other at the lower part and there is no longer any central jet. On the other hand 85 these valves are separated at their upper part, reducing to a minimum the section of the annular orifice. In this position of the valves, the annular jet escaping through the outer passage *g* is interrupted at *i* and *i'* 90 by the flanged side edges of the valves, said edges extending out to the upper edge of pipe *a* so that the flanges thus act as obstructions which result in the formation of gaps in the jet at the said points *i* and *i'*, the gaps 95 facilitating the mixing of the steam.

These valves are of rounded form, as is shown in Figs. 5 and 6, and they have a greater curvature toward the top than toward the bottom so that they conjointly 100 form a substantially conical element which is opened or closed according to the position of the valves; they are of very simple construction and do not need to be adjusted minutely. They have only, as a matter of 105 fact, to make an approximate joint one against the other at their lower part or to make an approximate joint against the blast pipe *a* at the upper part.

The device cannot be put out of order 110

owing to the fact that this pipe *a* is fixed and centered once for all. The valves are, on the other hand, perfectly balanced, the velocity of the steam has no influence upon them, and their action, which takes place without any friction, in no wise causes any wear on the operating parts the movement of which is furthermore, of very slight amplitude. The valves may be operated in different ways, for example, as shown in Fig. 7, by means of two gear teeth *j* and *j'* forming part of the pivot axle of one valve and engaging with each other. The operation of the valve may then be effected by the squared end *k* provided on one of the pivot axles.

In the constructional form represented in Figs. 8 to 11, the two valves *b* are pivoted to a common shaft *l* carried by the pipe *a*, instead of being pivoted independently of each other; in the open position of the cone which, incidentally, is the closed position of the pipe (see Figs. 8 and 9), the valves virtually form joints against the pipe *a*, and allow only the annular orifice *g* to exist, there being then no communication between the outer orifice or passage *g* and the central space or passage *f*. In the open position (see Figs. 10 and 11), the valves having quitted their points of support against the pipe, provide communication between the orifice or passage *g* and the central space *f*, and thereby leave a passage for the flow of the steam from the orifice *g* to the central orifice and its escape by the central orifice. These valves may be operated by two gear teeth *m* keyed on the same shaft *n*, or by any other device.

A blast pipe with a central and an annular section of evacuation may also be obtained by using the revolving cone device shown in Figs. 12, 13, and 14. The pipe *a* is provided, as will be seen, with ribs *o* serving to support the segments of conical surface *p* which define a space in which rotates, about a vertical axle *q*, a piece formed by the portions of the cone *r* in number equal to that of the segments *p*. In the open position of the blast pipe, there is a central passage *f* and an annular passage *g*, and, in the closed position, only this latter passage exists. The pipe may, it should be quite understood, be provided with corrugations, as in the arrangements with pivoted valves.

What I claim and desire to secure by Letters Patent of the United States is:—

1. A steam blast pipe of the character described, having arranged within it a pair of coacting valves, at least one of which is movable relatively to the other to open or close a central steam passage through them; said valves also providing a constantly-open, annular steam passage between them and the wall of the pipe; and means for operating the movable valve. 60

2. A steam blast pipe of the character described, having arranged within it a pair of pivotally-mounted, coacting valves movable relatively to each other to open or close a central steam passage through them; said valves also providing a constantly-open, annular steam passage of variable diameter between them and the wall of the pipe; and means for operating said valves. 70

3. A steam blast pipe of the character described, having a corrugated outlet end; a pair of coacting valves disposed within said pipe, at least one of which valves is movable relatively to the other to open or close a central steam passage through them; said valves also providing a constantly-open, annular steam passage between them and the wall of the pipe; and means for operating the movable valve. 75

4. A steam blast pipe of the character described, having arranged within it a pair of coacting valves, at least one of which is movable relatively to the other to open or close a central steam passage through them; said valves also providing a constantly-open, annular steam passage between them and the wall of the pipe; cross-rods fixed to the tops of the rods; and a pivotally-mounted lever for operating the valves having slots wherein the cross-rods are engaged. 90

5. A steam blast pipe of the character described, having arranged within it a pair of coacting valves, at least one of which is movable relatively to the other to open or close a central steam passage through them; said valves also providing a constantly-open, annular steam passage between them and the wall of the pipe; means for operating the movable valve; and means for interrupting the jet escaping at the mouth of the annular passage. 100 105

In testimony whereof I have signed this specification.

EMILE HARLET.
